UNITED STATES PATENT OFFICE

2,098,639

CARTON

Edwin A. Walther, Sandusky, Ohio, assignor to
The Hinde and Dauch Paper Company, San-
dusky, Ohio, a corporation of Ohio

Application November 15, 1935, Serial No. 49,980

2 Claims. (Cl. 229—27)

This invention relates to a ventilated carton, usually to be made of corrugated board, and particularly adapted for shipping a plurality of individual retailer containers of berries or other small fruits. For example, the form illustrated is made up to hold twenty-four quart-size berry boxes in three tiers of eight each, all separated from one another by elements of the carton and each box adjacent two or more ventilating openings. Ventilation within the box as well as to the outside is provided.

A further important feature of my invention is the self-locking of the tops and bottoms by means which are readily reached intentionally from outside but which are entirely protected and concealed and cannot be accidentally undone. These locking means require no fastenings whatever, such as staples, stitching, adhesive, or tape, and do not interfere in any way with printing on the surface of the carton. Furthermore, the self-locking means do not necessitate any additional openings in the carton beyond those which are required for other purposes.

Another feature of my invention is the provision throughout the interior of elements which serve the double purpose of strengthening the entire carton against vertical compression, thus preventing any crushing strains or vertical pressure coming upon the fruits in the contained retail packages, and also serve as separators for the retail packages.

To the accomplishment of the foregoing and related ends, said invention, then, consists of the means hereinafter fully described and particularly pointed out in the claims.

The annexed drawings and the following description set forth in detail certain structure embodying the invention, such disclosed means constituting, however, but one of various structural forms in which the principle of the invention may be used.

In said annexed drawings:

Fig. 1 is a perspective illustrating the several features of the carton, the external walls being broken away to illustrate the interior structure;

Fig. 2 is a corresponding perspective taken from an interior view point and looking outward and upward to show the locking means;

Fig. 3 is a longitudinal vertical section on the plane 3—3 of Fig. 5, but showing slightly modified venting;

Fig. 4 is a transverse vertical section on the plane 4—4, Fig. 5;

Fig. 5 is a horizontal section on the plane 5—5, Fig. 3; and

Fig. 6 is a perspective of the carton closed and ready for shipment.

Externally my improved carton comprises a box which has the top and bottom formed of two tuck flaps 1, 1, each preferably half the box width, and is provided with a considerable number of ventilation and other openings, such as 3, 5, 7 and 9, of various sizes and shapes. Internally it is divided into a plurality of layers, three in the present embodiment, by horizontal pads 11 and 13, and is divided longitudinally and transversely by various elements which are vertically aligned with corresponding elements in other layers. All of the various interior pads and dividing partitions are cut with a sufficient quantity of ventilating openings, many of which allow circulation of air to more than one compartment of the carton. The interior of the carton is thus divided into a plurality of compartments, those at each end being preferably of a size to receive only a single retail container and those in the middle to receive two longitudinally adjacent retail containers, all of said containers being separated laterally and horizontally by elements of the carton and many of them being also separated longitudinally by carton elements.

The top and bottom are identical in construction and can best be understood by reference to Fig. 1. Each tuck flap 1 comprises in detail a flap portion 15 and a tuck portion 17, between which a score line 19 runs lengthwise of the carton for bending. Only the portions 15 are visible when the carton is closed as in Fig. 6. At each end of the tucks 17 there is a locking tab 21 scored along the edge 23 where it adjoins 17. The locking tabs begin only a slight distance from the score line 19, just sufficient to leave a space 25, approximately equal to the thickness of the material, and extend along the edge of 17 as far as may be necessary for strength, about half way in the illustrated embodiment. The length of the tabs 17 in the direction of the fold line 19 is slight, in order that the tabs may be swung to and from locking position without striking the retail packages in the carton.

Two inner flaps are formed integral with each end and are bendable at 27 and 29 into a horizontal panel 31 and a vertical panel 33. These flaps are not quite half the box width, being sufficiently spaced along the central plane of the carton to permit entry of the two tucks 17, as is best seen in Figs. 1 and 2. When the carton is to be closed, each of the tabs 21 is folded down onto its adjacent tuck 17, whereafter the two tucks 17 are pushed down through the slot 55

between the respective panels 31—31 and 33—33. The depth of these tucks 17 is equal to the depth of the vertical partition panels 33, which is the distance from the top of the carton to the first 5 horizontal pad 13, or from the bottom of the carton to the lower horizontal pad 11, as the case may be. When the flaps 17 are fully down, the edges of the tabs 21 which are next to the cuts 25 are sufficiently clear of the panels 31 to 10 allow the natural resiliency of the corrugated board to spring the tabs out approximately to the position indicated in dotted lines at 21' in Fig. 1, thus locking the tucks 17 beneath the panels 31, and so locking the lid, or bottom as 15 the case may be, shut. These panels 31 are thus in turn held down beneath the top 15, so that so long as the tabs 21 are sprung out to any degree past the slot 34, the various top elements will all remain securely interlocked.

20 The openings 7 in each end near the top of the carton serve the dual purpose of hand holds and of permitting finger access to the tabs 21, whereby the latter can be turned back against the tucks 17 to allow these tucks to be pulled out 25 and so open the carton.

The members 33 act as part of the vertical load-carrying structure and also constitute spacers or partitions between certain of the packed retail containers. The additional interior structure of the carton comprises vertical longitudinal pads, such as 35, preferably of double thickness for strength, as shown, and transverse vertical pads, such as 37, interlocking therewith in the usual manner by half-depth slots 39 and 35 41, and extending the full width of the carton. This internal cellular construction, in conjunction with horizontal pads, is not essentially a part of my invention, but it cooperates with the features of the invention in that the tucks 17 40 are in vertical alignment with the vertical pads 35 and the panels 33 are in vertical alignment with the transverse vertical pads 37. The interior cellular subdivision may be carried as far as desired.

45 All of the interior partitioning elements of the carton, such as 17, 31, 35 and 37, are notched by openings, such as 43, of ample proportions to permit free circulation of air, and preferably so spaced that every partition is notched adjacent every retail container in the carton.

50 The horizontal pads are similarly ventilated by notched openings, such as 45, along their edges, placed according to the same governing principles, and also by holes, such as 47, at the intersections of longitudinal and transverse par-

titioning elements, these holes 47 being conveniently so sized that each hole gives in effect an opening into each of the four angles at each partition intersection.

From the foregoing it will be seen that I have 5 provided a shipping container particularly adapted for construction out of corrugated board, which combines interlocking features peculiar to itself with spacing and ventilating features hitherto known in the art, all in such a manner 10 that a minimum of loose pieces are required, and a considerable part of the material used serves multiple functions for strengthening the carton, spacing the contents, and locking the carton, all without unnecessary duplication of parts. 15

The carton is also characterized by the features of symmetry and of economy of material. In making up and assembling the entire carton, the only fastening required, in addition to the box material itself, is along one vertical edge of 20 the carton such as the edge 49, Figs. 5 and 6, where a flange 51 is secured by means of staples 53 or other appropriate fastening to unite the sides of the carton into a continuous structure in the usual manner.

25 Other modes of applying the principle of my invention may be employed instead of the one explained, change being made as regards the structure herein disclosed, provided the means stated by any of the following claims or the 30 equivalent of such stated means be employed.

I therefore particularly point out and distinctly claim as my invention:

1. In a carton of the character described, in combination, end-hinged panels laterally divided, 35 cover flaps substantially equal in width to the width of said divisions and adapted when folded to overlie said panels, a tuck on each of said flaps, said tucks being adapted to pass down between the adjacent edges of said panels, and 40 lock tabs hinged to said tucks at a right-angle to the flap-tuck bend line and having an edge substantially in the plane of said line.

2. In a carton of the character described, in combination, end-hinged panels laterally divided, 45 cover flaps substantially equal in width to the width of said divisions and adapted when folded to overlie said panels, a tuck on each of said flaps, said tucks being adapted to pass down between the adjacent edges of said panels, lock tabs 50 hinged to said tucks at a right-angle to the flap-tuck bend line and having an edge substantially in the plane of said line, and access openings in the box ends adjacent said lock tabs.

EDWIN A. WALTHER.
